PULP SCREEN

Application filed July 17, 1931. Serial No. 551,467.

This invention relates to pulp screens used in the manufacture of pulp and paper products and particularly to flat screens equipped with cam operated diaphragms arranged beneath the screen plates.

The purpose of the invention is to provide a generally improved and more compact assembly in which the diaphragm is carried by a metal frame and the cam shaft 10 is positioned close to the underside of the diaphragm in bearings forming part of said frame. This revised assembly permits the cam shoe fittings to be made shorter and more resistant to deflection than heretofore and 15 it also reduces deflection of the cam shaft by adequately supporting the shaft throughout its length in bearings rigid with the diaphragm frame. It also lends itself to the use of a desirable arrangement of coil springs 20 for holding the cam shoes to the co-operating cams and has other mechanical advantages not found in the ordinary assembly.

In accordance with this invention, the diaphragm is attached to wooden strips inlaid 25 in the upper portion of a metal frame which is clamped or otherwise secured to the bottom of the screen vat, said frame being cast with suitable passages for discharging the screened pulp from the space reserved between the screen plates and the underlying diaphragm. The cam shaft is carried in a 30 sectional bearing comprising an upper portion integral with the metal diaphragm frame and a lower portion consisting of separate sections bolted to the upper portion. The cam shoes are attached to metal fittings at the underside of the diaphragm and the upper portion of the cam shaft bearing is provided with cam shoe receiving slots located 35 directly above the cams carried by the shaft. The cam shoe fittings and the upper portion of the shaft bearing are provided with slidably engaging surfaces serving to resist lateral deflection of the cam shoes and are 40 connected together by spring connections arranged to hold the cam shoes to the co-operating cams.

Proceeding now to a more detailed discussion of the invention reference will be had 45 to the accompanying drawings, in which—

Fig. 1 is a longitudinal sectional view through a screen assembly constructed in accordance with this invention.

Fig. 2 is a transverse sectional view along the line 2—2 of Fig. 1.

Fig. 3 is a plan view of the metal diaphragm frame.

Fig. 4 is a side view of the diaphragm frame.

Fig. 5 is an end view of the diaphragm frame.

Fig. 6 is a sectional view along the line 6—6 of Fig. 3.

Fig. 7 is a sectional view along the line 7—7 of Fig. 3.

Fig. 8 is a sectional view along the line 8—8 of Fig. 3.

Fig. 9 is a sectional view along the line 9—9 of Fig. 3.

Fig. 10 is a sectional view along the line 10—10 of Fig. 3.

Fig. 11 is an enlarged plan view of a portion of the diaphragm frame appearing in Fig. 1.

Fig. 12 is a side view of one of the cam shoe fittings.

Fig. 13 is a bottom plan view of the fitting shown in Fig. 12.

Fig. 14 is a perspective view of one of the cam shoes.

Fig. 15 is a side view of the cam shaft.

In these drawings the ordinary screen vat appears at 11 and is provided with the usual arrangement of screen plates 12. The diaphragm 13 is attached to wooden strips 14 inlaid in the upper portion of the metallic diaphragm frame 15. The marginal portion of the frame is formed by vertical side walls 16 and vertical end walls 17 provided with inwardly projecting flanges 16a and 17a positioned below the upper edges of the walls. The central portion of the frame is braced at intervals by T-shaped cross members 18 presenting vertical portions 19 merging with the side walls 16 and horizontal portions 20 merging with the side wall flanges 16a. The longitudinal strips 14 to which the diaphragm 13 is secured are mounted on the flanges 16a while the transverse strips 14 are mounted on the flanges 17a and on the horizontal por- 100

tions 20 of the cross members; all of the strips 14 being bolted in place as indicated at 21 in Figs. 1 and 2 and having their upper surfaces flush with the upper edges of the walls 16 and 17.

The frame 15 is cast with a plurality of passages 23 for conducting screened pulp from the space between the screen plates and the diaphragm to the inlet 24 of the usual pulp receiving vat 25. The outer end of each passage communicates with the vat inlet 24 through an opening 26 in one of the side walls 16 while the inner end of said passage communicates with the space between the screen plates and the diaphragm through an opening 27 in the adjacent flange 16a. At the upper surface of the flange each opening 27 is bounded by vertical side and end walls 28 and 29 forming a supplementary passage leading from the opening 27 to a similar opening 30 in the diaphragm 13.

The cam shaft 31 carries the usual cams 32 and is journalled in a bearing comprising an upper section 33 and a plurality of lower sections 34 bolted together as indicated at 36. The upper section 33 is cast integral with the end walls and cross members of the frame 15 and is reinforced at these members by suitable stiffening flanges 33a. The bearing sections 33 and 34 are formed with mating half casings 33b and 34b affording housings enclosing the cams 32. The upper portion 33b of each cam housing is provided with a slot 37 for the entrance of a cam shoe 38 co-operating with the cam 32.

Each shoe 38 is carried by a metal fitting comprising a base plate 39 provided with depending side flanges 40 and with a depending transverse rib 41, the latter extending across the central portion of the plate between the side flanges. The base plate 39 is secured by bolts 42 to the usual oak plate 43 engaging the lower side of the diaphragm 13 and the cam shoe 38 is secured to the plate 43 by bolting the shoe to one side of the rib 41 as indicated at 44.

A pair of spring sockets 45 are cast integral with the upper half 33b of each cam housing and are arranged at opposite sides of the cam shoe receiving slot 37. The spring sockets are closed at their upper ends except for small openings 46 through which extend bolts 47 having their upper ends fastened to the plate 39 as indicated at 48. The lower ends of these bolts are equipped with nuts 50, supporting washers 51 fitted in the lower ends of the spring sockets. Coil springs 52 are arranged in said sockets to exert downward pressure on the washers 51 so that the cam shoes 38 are thereby held down upon the co-operating cams 32.

At the sides remote from the intervening slot 37 the spring sockets 45 are provided with flat surfaces 53 disposed in sliding engagement with suitable guide pedestals 54

depending from the plate 39. The sliding engagement thus obtaining between the spring sockets and the pedestals constrains the guide shoe to a straight line vertical movement and thereby practically eliminates lateral deflection of the shoe. The bottom portion of the frame 15 may be provided, as shown in Fig. 2, with suitable inwardly directed base flanges 56 adapted to be secured upon the upper ends of the supporting legs 57. In the present instance the supporting legs 57 are shown as made of concrete but it will be understood that the usual metal supporting legs may be substituted if desired.

The diaphragm frame 15 may be clamped or detachably secured to the bottom of the screen vat 11 in any desired manner. In the present instance I have shown conventional clamps comprising eye bolts 59 equipped with links 60 engaging over hooks 61 carried by the screen vat 11. The lower ends of the eye bolts extend downwardly through lugs 66 carried by the frame 15 and are equipped with tightening nuts 67.

The construction described in the foregoing has numerous advantages in comparison with the conventional screen vat and diaphragm assembly. The cam shaft is adequately supported against deflection by mounting the shaft in bearings rigid with the non-sagging metal frame to which the diaphragm is attached. This arrangement also brings the shaft close to the underside of the diaphragm so that the cam shoes may be directly attached to short depending ribs 100 carried by a metal plate at the underside of the diaphragm with the result that the cam shoe fitting thus provided is more rigid and resistant to lateral flexure than the relatively long cam shoe fittings required in the conventional assembly, wherein the cam shaft is positioned an appreciable distance below the diaphragm. The mounting of the cam shaft close to the underside of the diaphragm also enables the cam shoe fittings and the shaft supporting frame to be interconnected in a convenient and desirable manner to hold the cam shoes to the co-operating cams and to assist in preventing lateral motion or deflection of the shoes.

Having thus described my invention, what I claim is:

1. A screen assembly of the character described including a screen vat, a diaphragm frame beneath the screen vat, a diaphragm attached to said frame, a cam shaft journalled in the frame beneath the diaphragm, and cam shoes depending from the diaphragm and engaging co-operating cams on said shaft.

2. A screen assembly of the character described including a screen vat, a metal diaphragm frame beneath the vat, a diaphragm carried by said frame, a cam shaft journalled in the frame beneath the diaphragm,

cam shoes depending from the diaphragm and engaging co-operating cams on said shaft, and means for exerting resilient pressure on the shoes in the direction of the cams.

5. A screen assembly of the character described including a screen vat, a metal diaphragm frame beneath the vat, a diaphragm carried by the frame, a cam shaft journalled in the frame beneath the diaphragm, cam shoes depending from the diaphragm and engaging co-operating cams on said shaft, and means rigid with the cam shoes and engaging the frame to resist lateral displacement of the shoes.

10. 4. A screen assembly of the character described including a screen vat, a metal diaphragm frame beneath the vat, a diaphragm carried by said frame, a cam shaft journalled in the frame beneath the diaphragm, cam shoes depending from the diaphragm and engaging co-operating cams on said shaft, means for exerting resilient pressure on the shoes in the direction of the cams and means rigid with the cam shoes and engaging the frame to resist lateral displacement of the shoes.

15. 5. A screen assembly of the character described including a screen vat, a diaphragm frame beneath the vat, a diaphragm carried by the frame, a cam shaft journalled in the frame below the diaphragm, cam shoe fittings at the underside of the diaphragm, cam shoes depending from the fittings and engaging co-operating cams on said shaft, and spring connections between the frame and the cam shoe fittings serving to hold the shoes engaged with said cams.

20. 6. A screen assembly of the character described including a screen vat, a diaphragm frame beneath the vat, a diaphragm carried by the frame, a cam shaft journalled in the frame beneath the diaphragm, cam shoe fittings at the underside of the diaphragm and cam shoes depending from the fittings and engaging co-operating cams on the shaft, said cam shoe fittings having portions slidably engaging co-acting portions on the frame to resist lateral displacement of the cam shoes.

25. 7. A screen assembly of the character described including a screen vat, a diaphragm frame beneath the vat, a diaphragm carried by the frame, a cam shaft journalled in the frame below the diaphragm, cam shoe fittings at the underside of the diaphragm, cam shoes depending from the fittings and engaging co-operating cams on said shaft, said cam shoe fittings having portions slidably engaging co-acting portions on the frame to resist lateral displacement of the cam shoes and spring connections between the frame and the cam shoe fittings serving to hold the shoes engaged with said cams.

30. 8. A metal diaphragm frame for screen vats equipped with a bearing structure for

the cam shaft, said bearing structure comprising an upper bearing section integral with the frame and a plurality of lower bearing sections detachably secured to the upper section.

35. 9. A pulp screen of the character described including a metal diaphragm frame equipped with a bearing structure for mounting the usual cam shaft, said structure comprising an upper bearing section integral with the frame and a plurality of lower bearing sections detachably secured to the upper section, said upper section being formed to provide half casings mating with similar half casings of the lower sections to provide housings for enclosing the cams carried by said shaft, each housing having a slot in the upper half for the passage of the co-operating cam shoe attached to the diaphragm.

40. In witness whereof, I have hereunto set my hand.

WILLIAM R. TIDMARSH.
